UNITED STATES PATENT OFFICE

2,502,374

BAG STACKING AND BUNDLING MACHINE

Benjamin Gilowitz, Bronx, N. Y., assignor of fifty
per cent to Albert Friedberg, Mount Vernon,
N. Y.

Application November 2, 1948, Serial No. 57,921

4 Claims. (Cl. 93—93)

1

This invention relates to a bag stacking and bundling machine, and has as its primary object the provision of apparatus for the stacking and forming into bundles of bags or similar articles fed thereto either mechanically or manually.

An additional object of the invention is the provision of a device of this nature whereby bags of cellophane or other material are adapted to be fed to a conveyer belt in predetermined numbered quantity, moved by the conveyer belt, aligned or stacked, and then fed to a binding tape in stacked relation.

A further object of the invention resides in the provision of means in association with such a device for feeding binding tape in predetermined lengths to a stack or quantity of bags or other flat articles to be bundled.

Still another object of the invention resides in the provision of means for applying glue or similar adhesive to an end of the tape simultaneously with the stacking and bundling operation to facilitate sealing of the tape about the bundle.

A still further object of the invention resides in the provision of means in association therewith whereby various types of bags or similar articles of different sizes may be readily handled by the machine.

A further and more specific object of the invention is the provision of a bag stacking and bundling machine particularly adapted to be utilized in conjunction with a bag-making machine of any suitable type. One type machine particularly adaptable for such use is the "Roto bag machine" manufactured by the Roto Bag Machine Corporation of 310 East Twenty-second Street, New York city, New York. The "Roto bag machine" is adapted for the forming of bags from heat-sealed coated materials such as cellophane, aluminum foil and the like, and is of a construction adapted to fabricated bags or envelopes of such material and seal the seams by the application of heat, feeding the articles outwardly of the machine as formed.

Still other objects reside in the provision of a device which is sturdy and durable in construction, reliable and efficient in operation, and relatively simple and inexpensive to manufacture, assemble and utilize.

Still other objects reside in the combinations of elements, arrangements of parts, and features of construction, all as will be more fully pointed out hereinafter and disclosed in the accompanying drawings wherein there is shown a preferred embodiment of this inventive concept.

2

In the drawings:

Figure 1 is a side elevational view of one form of apparatus embodying the invention, parts at one end of the machine being broken away.

Figure 2 is a top plan view, portions thereof being broken away and other parts omitted.

Figure 3 is a sectional view taken substantially along the line 3—3 of Figure 2 as viewed in the direction indicated by the arrows.

10 Figure 4 is a sectional view taken substantially along the line 4—4 of Figure 1 as viewed in the direction indicated by the arrows.

Figure 5 is a sectional view taken substantially along the line 5—5 of Figure 1 as viewed in the direction indicated by the arrows.

Figure 6 is a fragmentary sectional view similar to Figure 3, and taken along the same section line, but disclosing certain of the operative parts in a different position of adjustment.

20 Figure 7 is an enlarged sectional view taken substantially along the line 7—7 of Figure 4 as viewed in the direction indicated by the arrows, and

Figure 8 is a sectional view taken substantially along the line 8—8 of Figure 7 as viewed in the direction indicated by the arrows.

Similar reference characters refer to similar parts throughout the several views of the drawings.

30 Referring now to the drawings in detail, the device of the instant invention is comprised of a framework including four upright supports 10 of wood, metal or other material, positioned to form a rectangle, and adapted for the support of an intermediately positioned table generally indicated at 11. The table 11 includes longitudinally extending channel members 12, connecting adjacent posts, while transversely extending members 13 connect the lower extremities of oppositely disposed posts 10, and additional transverse channel member 14 connects on pair of posts 10, hereinafter referred to as the rear posts.

The other pair of posts 10, hereinafter referred to as the front posts are connected at an intermediate point above table 11 by means of an angle iron member 15. A longitudinally extending angle iron member 16 extends from one or rear posts 10 to the aligned forward post 10. Extending rearwardly from the other post 10 is a

40 horizontal plate 17, to the end of which is secured, as by rivets 18, a transverse plate 19, the opposite extremity of which is secured, as by rivets 20, to the horizontal portion or angle iron member 16. It will now be seen that there is provided a sturdy substantial rectangular frame

50

55

adapted for the support of table 11, and provided at one side with an open space extending from the extremity of member 17 to channel 14 at one side thereof, the purpose of which open space will be more fully described hereinafter.

Referring back to the table 11, it will be seen that a plate or sheet 25 extends transversely between longitudinally extending channel member 12, to provide a support for an endless belt 26, mounted for rotation on front and rear axles 27 and 28 respectively, the latter being suitably journaled in uprights or posts 10, extending transversely between the front and rear posts respectively. One of the axles, for example axle 27, is adapted to be driven in any desired manner, as for example by a sprocket 29 and chain 30, in such manner as to rotate belt 26 so that its upper surface moves in a direction toward front posts 10. While the chain 30 may be driven in any desired manner, when the apparatus is utilized in conjunction with the above mentioned "Roto bag machine" it may be driven by the motor of the latter in such manner that the speed of travel of the belt is synchronized with the bag making machine, for a purpose to be described more fully hereinafter. Conversely the apparatus may be driven by its own motor or if desired by a hand crank (not shown) which may be substituted for the sprocket 29.

Journal cover plates 31 secured to posts 10 as by means of screws 32 are preferably employed to hold axles 27 and 28 in related assembly with their associated journals in the posts 10.

Belt 26 is provided with a plurality of transverse rows of lugs or fingers 35. As shown in the drawing, there are two rows and each row has three lugs transversely aligned across the belt. Each of the lugs 35 extends a substantial distance perpendicularly of the belt 26, and is provided at its upper extremity with a beveled or inclined surface 36, the direction of inclination being downward from the rear of the apparatus towards the front. Lugs 35 may be made of any desired material and secured in any desired manner to the endless belt which is preferably made of canvas although other materials may be used. The belt 26 also carries a single, centrally and circumferentially extending row of relatively closely spaced rectangular lugs 37 of any suitable material and secured in any desired manner for a purpose which will be more fully described hereinafter.

A bag, envelope, or other article supporting table, generally indicated at 40, is positioned directly above belt 26, and is comprised of outer longitudinally extending channel members 41, oppositely disposed and between which extend horizontally spaced strips 42. As best shown in Figure 3 members 41 and 42 extend a substantial distance forwardly and rearwardly of axles 27 and 28 respectively. The forward extremities of the members 41 and 42 are secured to transversely extending plates 43 and 43a extending across the top of an arcuate casing member 44, the latter including end plates 45 secured as by angle iron members 46 and rivets 47 and 48 to front posts 10. As shown in Figure 2 the strips 41 and 42 are spaced apart by filler plates 50 also secured to the plates or strips 43 and 43a. The upper surfaces of plates 50, strips 42 and the horizontal flanges of angle strips 41 are in the same horizontal plane to provide a flat surface over which a stack of bags may be slid as later explained. Plates 50 extend rearwardly only to a point substantially adjacent the forward extremity of front posts 10.

The rear extremities of members 41 and 42 are supported by a transversely extending plate or strip 51, and are secured thereto by rivets 52. The plate 51 is positioned in a transversely extending arcuate guard or casing member 53, which includes end plates 54. The latter are each secured by rivets 55 to one flange of an angle iron 56, the other flanges of which are secured by fastenings 57 to the rear posts 10.

Secured to the horizontal flange of each member 41 and each strip 42 at a point adjacent the forward sides of rear posts 10 are a plurality of spaced but aligned angle iron members 60. The horizontal flanges of the short angle members 60 are secured by rivets 61 on the strips 41 and 42. The vertical flange of each member 60 has secured thereto by rivets 62 the lower extremity of a depending plate 63 of a width equal to the width of the strips 42 and the horizontal flanges of the members 42 as seen in Figure 5. It is here pointed out that the horizontal flanges of members 41 and strips 42 are substantially equal in width. The upper extremities of the transverse row of plates 63 are secured as by means of rivets 64 to the forward depending flange of channel member 14.

The operation of that portion of the machine so far described should now be readily understandable. Bags, envelopes or the like are fed onto the table comprised of members 41 and 42 through the opening in the side of the apparatus adjacent the sprocket wheel 29, that is, between the plates 17 and plates 63. The bags may be thrown in by hand or may be discharged by a bag making machine directly into the device adjacent the plates 63 one after another so that they form more or less of a pile or stack on the strips or members 41 and 42. Rotation of belt 26 will now cause a row of aligned fingers 35 to abut the rear edges of the bags, thus aligning their edges transversely of the apparatus, and moving them forwardly, as for example, from the position disclosed in Figure 3 wherein the bags are designated by the reference character 70, to the position as shown in Figure 6, from which latter position they 45 may be moved for further operation in a manner to be more fully described hereinafter. Figure 5 discloses in dotted lines the relative position of a bag 70 during insertion into the apparatus.

Means are provided for accommodating the apparatus to different sizes of bags, and may take the form of mechanism generally indicated at 71 adapted for the accommodation of bags of various lengths, the length illustratively being considered as the dimension of the bag transversely of the apparatus. Further means are provided and generally indicated at 72 for the accommodation of bags of various widths, the width of the bag being considered for illustrative purposes as that dimension of the bag extending longitudinally of the apparatus. Referring first to the mechanism 71, there is disclosed in Figure 2 an L-shaped bracket plate 75, one end of which is secured as by a fastening 76 to the horizontal flange of member 14, and the opposite extremity of which 55 is secured as by a fastening 77 to the horizontal portion of member 14. The transversely extending leg of L-shaped member 75 is channel-shaped and extends a substantial distance across belt 26. Its top is provided with a slot 78, in which is 60 adapted to move a set screw 79, the latter extending through a channel-shaped member 80 which telescopes and is slidable along the member 75. A nut 79a in channel member 75 engages screw 79 permitting locking of the parts. Secured to 65 75 opposite sides of the depending flanges of chan-

nel-shaped member 80 are angle brackets 81, in aligned relation, which brackets are in turn secured to a vertically positioned bag stop plate 82. Plate 82 is of generally rectangular shape having its rear vertical edge disposed to clear the plates or strips 63 and its bottom edge to clear strips 41 and 42. At its lower end is an extension or flange 83. It will now be seen that bags entering the apparatus in the manner previously described will abut the plate 82 and its extension 83, thus aligning them transversely of the apparatus. Obviously the plate 82 may be positioned in desired relationship transversely of the apparatus to accommodate a desired length of bags, it being noted that the plate must be positioned above either one of strips 42 or the horizontal flange of member 41, in order to prevent interference with the free passage of lugs 35.

Referring now to the mechanism generally indicated at 72 for the accommodation of bags of various widths, it will be seen that there is provided a plurality of spaced parallel longitudinally extending strips 85 having arcuate and upwardly turned extremities 86. Each outermost strip 85 has secured thereto the horizontal flange of an angle iron member 87, the vertical flange of which is adapted to be positioned exteriorly of the vertical flange of adjacent member 41 for longitudinal sliding movement therealong. The front extremities of strips 85 are held in aligned related assembly by means of a transverse strip 88 secured to each of members 85 as by a rivet 89 (see Figure 6). The rear extremities of the members 85 are secured in related assembly as by means of rivets 90 extending through a transversely extending strip 91 positioned a substantial distance above members 85 by means of spacing collars 92. It will thus be seen that the assembly comprised of connected strips 85 may be moved longitudinally along the members 41, and thus be suitably positioned to accommodate various widths of bags, envelopes or the like.

Means are provided for applying binding tape or the like to the package of bags passed forwardly of the machine by lugs 35, the package being moved longitudinally of members 41 and 42 and beneath plates 85 by the lugs 35 in the manner previously described. The tape applying means may take the form of an inverted U-shaped bracket member 95, the depending legs of which are secured as by rivets 96 to the outer sides of the forward posts 10 as shown in Figure 4. Centrally positioned on the horizontal portion of member 95 is a pair of oppositely disposed spool mounting brackets 97, the securing means taking the form of nuts and bolts 98. Extending between the upper extremities of bracket 97 is an axle 99, which carries inwardly of the bracket a pair of spaced serrated or toothed wheels 100, between which is fixed a spool carrying a roll of tape 101 adapted to be positioned about the packages of bags. The tape 101 extends downwardly through a vertical guide bracket 102 secured to the vertical flange of transverse member 15, and thence forwardly to a horizontally positioned guide 103 carried by a transverse plate 104 extending between the two intermediate plates 85. The guide 103 is in the form of a rectangular plate secured at one of its corners by a rivet as shown in Figure 2, to the plate 104 and with a small spacer beneath it so that the guide plate 103 is spaced slightly above plate 104. The tape may therefore be readily slid laterally beneath the guide plate. From the guide 103 the tape is then adapted to pass downwardly between the mem-

bers 85 to a second guide 105 which is similar to 103 and positioned on the bottom of plate 43a, as seen in Figure 3. From guide 105 the tape 101 extends further downwardly to a guide 106 carried by an adhesive dispensing member generally indicated 107 and to be more fully described hereinafter. It may be here pointed out that all of the brackets or guides 102, 103, 105 and 106 take the form of extending lugs or plates spaced parallel to their adjacent supporting surfaces, and secured to such surfaces only at one end, whereby the tape may be inserted in each guide bracket from the open end with a minimum of effort and difficulty.

15 It will now be seen that as the bags are moved to the position disclosed in Figure 6, a sufficient quantity of tape, the tape having previously been passed through the above-mentioned guides, is unwound and extended by pressure of the bags 20 from the reel or drum supported by the axle 99, to completely encircle the package of bags. Obviously the greater the width of the bags the more tape will be unrolled from the reel.

Means for stopping the rotation of the reel, 25 and simultaneously severing the tape when a desired quantity has been unreeled are also provided. Such means may take the form of a series of fingers 110 provided with arcuate extremities 111 extending downwardly into the path of travel 30 of lugs 35 (see Figure 4). Fingers 110 are integral with a swinging plate 112 hingedly secured as by means of hinge members 113 to a depending flange 114 comprising a portion of member 95, the arrangement being such that abutment 35 of lugs 35 with fingers 110 will cause forward swinging movement of the plate 112. Secured to the central one of fingers 110 as by means of a rivet 115 is a curved arm 116 provided at its upper extremity with a dog or pawl in the form 40 of a transverse plate 117 of a width slightly in excess of the space between serrated wheels 100. Correspondingly secured to the central finger 110 adjacent the lower extremity of arm 116, is an L-shaped cutter carrying member 118 which 45 in turn has secured to it a tape cutting knife blade 119. The parts 118, 119 and the finger 110 which carries them may swing down between the two central members 85 as seen in Figure 3. With the parts in the position as shown in Figure 3 it will be seen that member 117 and blade 119 are in inoperative positions. However, when the parts move to the position disclosed in Figure 6 the lugs 35 abut the arcuate extremities 50 111 of the fingers 110, and move the locking dog 117 into engagement with the teeth of wheels 100, thus precluding further rotation of axle 99 and its associated tape reel. Simultaneously the movable knife blade 119 severs the tape as indicated in Figure 6 against or close to the edge of the horizontal flange of transverse member 15, the latter serving as a stationary cutter member.

It will be seen that the central finger 110 extends into the path of travel of lugs 35, which 55 upon striking its curved extremity tilts the above described assembly to a relatively small degree which is insufficient to cause pawl 117 or blade 119 to become effective. However this oscillatory movement imparted to the plate 112 and its associated fingers tends to cause said fingers to vertically align the bags 70 by forcing them backwardly against the lugs or fingers 35 thus precluding irregular alignment such as may occur 60 in the event of one bag abutted by the lugs 35 pushing forward a previously deposited bag be-

fore the latter is properly engaged and aligned by the lugs 35.

As previously stated means are also provided for supplying adhesive, such as liquid glue or the like, to the extremity of the tape. Such means takes the form of a brush holding member 120, comprised of a tube of rectangular cross-section slidably supported for longitudinal adjustment in an upright frame rising from the center of channel member 13. This frame comprises spaced brackets 123 riveted at 123 to member 13 and connected by an inclined plate 121 of U-shape as seen in Figure 8. The brush tube 120 is slidably supported in the U-shaped member 121 beneath guide strips riveted to the upwardly projecting arms of 121. It is frictionally held in adjusted position and may be adjusted endwise according to the width of the bags to be bundled. Each end of the member 120 is provided with a hinge 124 and 125 respectively, hinge 124 being secured to a closure plate 126 adapted to close the rear open end of tube 120, while hinge 125 is secured to a front closure plate 127 adapted to abut the bristles 128 of a brush 129. The brush 129 is secured in a groove in a mounting block 130. The brush and its block are inserted in tube 12 through its rear end with the bristles 128 extending outwardly beneath the cover 127 into juxtaposition with tape 101 and guide 106 (see Figures 7 and 8). Cover plate 127 is provided with a longitudinal slot 135 (see Figure 7) through which liquid adhesive may drop, as from a nozzle 136, onto bristles 128 for application to the tape.

The brush head 128 is preferably a flat layer of relatively stiff bristles the free ends of which hold the tape 101 against the flat guide plate 106 as seen in Figure 7. The end of the tape may be readily inserted in the guide as above explained and will be held by the bristles, although the operator can easily pull the tape out and as he does so the bristles will coat the end of the tape with the adhesive. The nozzle or tube 136 depends from an adhesive supply container tube 137, which is pivotally suspended as by means of a pivot 138 from mounting brackets 139 secured to the lower surface of member 44.

The container is swung to adjust it according to the location of slot 135 and it is frictionally held in its adjusted position by its pivotal connection. It will thus be seen that liquid adhesive may be applied drop by drop to the bristles 128, and thus a small quantity is applied to the end of tape 101 in such manner that when the tape is wound about the package of bags 70 the adhesive underside of tape 101 may be applied by the operator directly to the opposite severed end of the tape after it has been positioned around the package.

From the foregoing the operation of the entire apparatus should now be readily understandable. The members 71 and 72 are first adjusted in the manner previously described to accommodate the size of bags to be fed to the apparatus. It will be noted that the stop plate 82, the vertical flange of strip 41 at the open side of the frame, the vertical plates 83 and the ends 86 of strips 85 define an entrance area for the bags or other articles, and that such entrance may be varied in size in two directions or dimensions by adjusting the parts 82 and 85. Rotation of belt 26 is then started, either mechanically or manually as may be desired, and the bags fed into the open side of the machine onto the supporting table 42 in the manner previously described. As one row of lugs 35 reaches the

rear end of the stack of bags they are moved forwardly, as shown in Figure 3, beneath strips 85, the curved extremities 86 thereof serving as guides and precluding the passage of bags thereover. The speed of the belt in relation to the speed of the feed mechanism, or manual feed serves to determine the number of bags positioned in advance of a row of lugs 35, and the entire assembly is moved forwardly from the position shown in Figure 3 to the position disclosed in Figure 6. At this time tape 101 is extended in the manner previously described until the lugs 35 act on the coating fingers 110 to lock wheels 100 and move the blade 119 to sever the tape, also as previously described. The stacked bags extend a substantial distance beyond the end of table members 41 and 42 at the time the tape is cut. The operator then brings the two ends of the tape together as the stack leaves the machine. Obviously it requires only a simple manual operation on the part of the operator to glue the gummed extremity of the tape 101 to the opposite extremity thereof so the tape will surround the package. It will be noted that for the sake of clearness, a portion of one of the plates or strips 85 is broken away to show the engagement of one of the lugs 35 with the curved end of one of the fingers 116, and in Figure 3 the fingered plate 112 is shown inclined slightly in a forward direction.

Any kind of tape may be used and in some instances the glue need not be used. In such cases the ends of the tape, cord or flexible binder would have to be tied together. It will therefore be understood that the term "tape" comprehends any flexible strand or strip which may be used to fasten the stack in a bundle. When the dog 117 is not engaged with the wheels 100, the tape unwinds freely from the spool or reel but the operator may hold the tape above the guide 106 as the discharging stack of bags unreel the tape or the lower end of the tape may be secured against movement in any other manner as the discharging stack extends the tape.

In order to repeat the operation it is simply necessary to pull the tape manually from its spool, pass the same through guides 102, 103, 105 and 106 in order to render the apparatus ready for bundling the next stack of bags.

While in the foregoing the device of the instant invention has been described as particularly applicable to bags or envelopes, it will be readily apparent that any suitable rectangular flat articles may be handled by the machine.

As various embodiments may be made of this inventive concept, and as numerous modifications may be made in the embodiment hereinbefore shown and described, it is to be understood that all matter herein is to be interpreted merely as illustrative and not in a limiting sense.

I claim:

1. In a device of the character described, in combination, a supporting frame having an article entrance and an article exit, an endless belt rotatable in said frame, means for moving said belt, first lugs carried by said belt, a plurality of spaced article supporting strips carried by said frame above said belt, said first lugs being arranged for movement between said strips to move articles supported thereon from entrance to exit, tape carrying means on said frame, guide means to position said tape over said article exit for extension by articles passed therethrough, second lugs carried by said belt, pivotally mounted fingers carried by said frame and extending into the

path of travel of said first and second lugs, and a tape cutting member carried by one of said pivotally mounted fingers for actuation by at least one of said first lugs, said second lugs imparting oscillatory movement to said fingers for vertical alignment of stacked articles moved by first lugs.

2. The structure of claim 1 wherein the first lugs are arranged in alignment across said endless belt to form a transverse row.

3. The structure of claim 1 wherein said second lugs are closely spaced in a single centrally positioned row extending longitudinally or circumferentially of said endless belt.

4. The structure of claim 1 wherein the extremities of the pivotally mounted fingers are curved and said first lugs are provided with in-

clined extremities for coaction with the curved ends of said fingers.
